(57) **CLAIM**

The ornamental design for a motor vehicle, toy vehicle replica and/or other replica, as shown and described.

DESCRIPTION

FIG. 1 is a perspective view of a motor vehicle, toy vehicle replica and/or other replica showing my new design;

FIG. 2 is a front view thereof;

FIG. 3 is a rear view thereof;

FIG. 4 is a left side view thereof, the right side being a mirror image thereof; and,

FIG. 5 is a top view thereof.

The broken lines in the drawings illustrate portions of the motor vehicle, toy vehicle replica and/or other replica that form no part of the claimed design.

1 Claim, 5 Drawing Sheets
